SAFETY RAZOR

Nicholas Testi, New York, N. Y., assignor to Gillette Safety Razor Company, Boston, Mass., a corporation of Delaware

Application October 31, 1933, Serial No. 696,054

16 Claims. (Cl. 30—75)

This invention relates to safety razors of the type in which a thin flexible blade is clamped in position for shaving between two blade-clamping members, such as a cap and guard. The invention consists in a novel razor of this type organized and adapted to receive a blade presented transversely or in position crosswise of the cap and guard, and in which the blade is swung into longitudinal or shaving position by the usual operations of clamping the cap and guard thereon. A razor of this character presents many advantages in construction and operation. In the first place, it eliminates the necessity for loose parts which may be lost or mislaid in taking the razor apart to remove or replace a blade, and permits the cap and guard to be permanently secured together, so long as a limited separation is allowed sufficient to receive the blade in flat condition. In the second place, the user is relieved of the necessity of locating the blade in shaving position since he has only to insert it between the cap and guard and then rely upon a mechanical positioning of the blade through the normal operation of the clamping mechanism. Further a razor organized as above outlined is adapted for use in combination with a magazine loader which may be temporarily engaged with the razor and operated to supply a blade transversely between the cap and guard, and thus the user is relieved of the necessity of in any way touching the sharp blade or impairing the keenness of its edge by accidental contact with dulling objects.

These and other features of the invention will be best understood and appreciated from the following description of a preferred embodiment thereof, selected for purposes of illustration and shown in the accompanying drawing, in which,—

Fig. 1 is a view of the razor in side elevation with a portion of the handle shown in cross-section;

Fig. 2 is a view of the head of the razor in side elevation, showing the cap and guard in blade-receiving relation;

Fig. 3 is a view of the razor in longitudinal cross-section;

Fig. 4 is a view of the razor as seen from the top, a portion of the cap being shown as broken away;

Fig. 5 is a view of the razor head in longitudinal section, showing the cap in the position which it occupies at the end of the blade-clamping operation;

Fig. 6 is a similar view showing the cap in its elevated or blade-receiving position;

Fig. 7 is a view in perspective of the blade-swinging and clamping spindle;

Fig. 8 is a plan view of one form of blade adapted for use with the razor illustrated, showing the blade-swinging key in cross-section; and

Fig. 9 is a plan view of the cap as seen from beneath.

The cap or blade backing member 10 is rectangular in outline and provided with an inner concave blade-engaging face. It has also thin parallel edges which are adapted to flex the blade over the face of the guard and maintain it for shaving in a position of pronounced transverse curvature. The cap is provided at each corner with a downwardly extending hooked corner lug 15 11 or 12. The lugs 11, on diagonally opposite corners of the cap, are thickened and serve as limiting stops for the blade as will presently be explained. The lugs 12 on the other two corners of the cap are thinner and are located outside 20 the rotary path of movement of the blade. All four lugs are extended beneath the guard so as to prevent separation of the cap and guard while permitting a limited relative movement of separation between the two. The cap is also provided 25 with spaced blade-locating pins 14 and with a central recess or slot 13 of keyhole outline, best shown in Fig. 9, disposed transversely of the cap and surrounded by circular countersunk shoulders.

The guard 18 which cooperates with the cap is provided with a pair of parallel shoulders, making a generally convex blade-engaging surface, and with guard teeth 19 at either longitudinal edge thereof. It is provided also with 35 spaced recesses 20 located in alignment with the blade-locating pins 14 and with a central recess 21 shaped to receive the ears of the key 27. The cap and the guard cooperate to flex the blade and support it adjacent to its cutting edges 40 when clamped in shaving relation.

The guard 18 is herein shown as formed integral with a tubular head 22 which forms a part of the handle of the razor. This is shouldered at its lower end to receive a hollow barrel 23. 45 Arranged to slide within the bore of the tubular head 22 is a cylindrical head or plunger 25 from the upper end of which projects a stem 26 carrying a flat key 27 having outwardly projecting ears at its upper end. The key 27 is proportioned to pass through the keyhole slot 13 of the cap and, when turned into a position parallel to its longitudinal axis, the ears positively engage the countersunk shoulders of the cap. The movement of the cylindrical head 25 is controlled, ex- 55

cept when there is a blade in the razor, by a U-shaped slot 28 therein which cooperates with a pin 29 projecting inwardly from the barrel of the handle. Below the head 25 is a threaded cylindrical stem 30 and below this is a long reduced shank 31 terminating in a riveted button. A long cylindrical nut 33, referred to as an operating device, is freely mounted within the barrel 23 of the handle. The threaded stem 30 fits within the upper end of the nut 33 which is resilient in character, being provided with longitudinal slots 34 for this purpose. The nut is provided with a reduced intermediate section and at its lower end with a cylindrical knurled head 35 for the convenience of the user in turning the nut. The cylindrical nut has a longitudinal bore in which is received the elongated shank 31 of the head 25, and the button of this shank is received in a recess provided therefor in the end of the head 35.

The nut 33 may be screwed up or down upon the threaded stem 30 so long as the end of the shank 31 extends freely into the recess in the head 35, but when this movement is exhausted and the button bottoms in its recess, the nut 33 and the head 25 turn as one piece if permitted to do so by the key 27 and slot 28. Also, while the key 27 is disposed transversely, as shown in Fig. 6, the nut 33 and head 25 may be slipped freely up and down in the handle of the razor an amount equal to the distance between the lower end of the barrel 23 and the upper end of the head 35. This is sufficient to carry the ears of the key 27 into position above the countersunk shoulders of the cap 10. The nut 33 and head 25 may also be turned 90° as a unit when the pin 29 occupies a position in the transverse part of the U-shaped slot 28.

The razor herein shown is adapted for use with thin flexible double-edged blades of well-known commercial type. A blade 40 of such type is shown in Fig. 8. It is provided with an elongated blade-locating slot 41, substantially as long as its cutting edge, and is recessed in each corner, thus defining elongated unsharpened end portions in the blade. The slot 41 is provided with spaced enlargements to receive blade-locating pins of corresponding shape and with a central enlargement of circular outline. The key 27 and its stem 26 are shaped to fit the central enlargement and fill the slot 41. The thickened corner lugs 11 are so disposed as to engage the unsharpened end portions of the blade and act as stops when the latter has been located concentric with the axis of the stem 26 and rotated about this axis between the cap and guard members of the razor.

When no blade is in the razor the key 27, the head 25 and the nut 33, acting as one piece, occupy their lowermost position in which the ears of the key 27 are received in the recess 21 of the guard and the pin 29 occupies a position near the upper end of one side of the slot 28 in the head 25. In this condition the cap 10 is held in place only by the hook lug 11 and 12, so that it may be readily lifted from the guard 18 to permit the introduction of a blade crosswise between the cap and guard members. The blade may be thus supplied either by hand or by a loading device and advanced transversely of the razor until it reaches a central position as shown in Fig. 4, that is to say until it is located symmetrically in the razor. The upper edge of the key 27 projects slightly above the bottom of the guard 18 so that it may enter the slot 41 of the

blade and center the latter during its movement of presentation. As soon as the end of the blade 40 has been introduced between the cap and the guard, the blade will serve to hold the cap resiliently away from the guard as indicated, for example in Fig. 2 of the drawing. When the blade has been presented and centered the head 35 is pushed upwardly and the key carried up through the slot of the blade and the keyhole slot 13 of the cap until its ears clear the countersunk shoulders of the cap. In this position the flat body of the key fills the slot of the blade as indicated in Fig. 8. The head 35 may now be turned through 90° and the blade 40 rotated with it from the crosswise position shown in Figs. 2 and 4 to the longitudinally disposed position shown in Fig. 5. This, as already explained, is determined by the engagement of the end portions of the blade with the stop lugs 12 of the cap. Rotary movement of the blade and the key is thus arrested with the ears of the key in interlocking relation with the cap 10. Further turning in the same direction of the head 35 at once becomes effective to screw the threaded stem 30 downwardly into the nut 33, thus, through the ears of the key, drawing the cap 10 downwardly into clamping engagement upon the blade. The parts of the razor are shown in Fig. 5 in the position they occupy at the end of this movement. The clamping movement continues until the cap 30 has been drawn tightly down upon the blade, flexing it transversely and finally clamping all the parts in shaving relation, as indicated in Fig. 1.

There is sufficient clearance in the horizontal portion of the slot 28 to permit the shoulders of the blade 40 to be brought into firm engagement with the stop lugs 11 of the guard before the pin 29 in the slot limits the rotary movement of the head 25. If no blade is in the razor the pin 29 becomes effective to prevent further movement of the head.

It will be noted that so long as the blade 40 is in engagement with the edges of the cap 10 the latter is held away from the guard to such an extent that the blade-locating pins 14 do not engage the blade. It is only after the blade has been swung into its longitudinal position and the cap allowed to approach the guard that the pins 14 enter the slot 41 of the blade.

When it is desired to remove the blade for cleaning or replacement the head 35 is rotated in the reverse direction. The head 25 at first is prevented from rotation on account of the engagement of the flexed blade with the pins 14 and the engagement of the key 27 with the blade accordingly, as the threaded stem 30 is turned it is screwed upwardly and out on the nut 33 until the cap has been lifted sufficiently to disengage the pins from the blade. When this occurs the stem 30 is free to turn with the nut 33 and the blade is swung through 90° into its crosswise position where it is arrested by the action of the pin 29 in the slot 28. The key 27 may now be allowed to drop through the blade into its recess in the guard leaving the blade free to be withdrawn transversely from between the cap and guard members.

Having thus described my invention, what I claim as new and desire to secure by Letters Patent is:—

1. A safety razor having elongated cap and guard members connected for limited separating movement, whereby a blade may be presented endwise and transversely between them, and

means located at all times in the razor for engaging and swinging into longitudinal position with respect to the cap and guard members a blade so presented.

5. 2. A safety razor having cooperating blade-clamping members connected for a limited movement of separation, whereby a blade may be presented crosswise between them, and means operating first to swing said blade 90° into longitudinal position with respect to the blade-clamping members and then operating to draw the clamping members into blade-flexing relation.

10. 3. A safety razor having cooperating blade-clamping members connected for a limited movement of separation to receive an interposed blade presented endwise in transverse position between them, a blade stop on one of said members, an operating device and mechanism actuated thereby first to swing the blade until the latter is positively arrested by said stop and then to draw said members into blade-flexing relation.

15. 4. A safety razor having cooperating blade-clamping members, connecting means for maintaining said members in spaced superposed relation to receive a blade presented transversely between them, a blade stop, and operating means including a blade swinging device and threaded elements frictionally connected thereto and arranged to be brought into operation when the 20 blade is arrested by engagement with the blade stop to draw said blade-clamping members toward each other.

25. 5. A safety razor having cooperating blade-clamping members, connecting means for maintaining said members in spaced relation to receive a slotted blade presented endwise and transversely between them, a key for engaging the slot of a blade so presented, operating means frictionally connected with said key, a blade 30 stop acting to limit the turning movement of the key by engaging the blade when its edge is moved into shaving position, and threaded elements actuated thereafter by said operating means for drawing the blade-clamping members together.

35. 6. A safety razor having cooperating blade-shaping members with cooperating curved faces, means for limiting said members to separation permitting a thin, internally-apertured, flexible 40 blade to be presented endwise and transversely therebetween in flat condition, blade-locating projections disposed out of the path of the presented blade, and means for swinging the blade, while the blade acts to hold apart said blade-shaping members, to register its aperture with 45 said blade-locating projections.

40. 7. A safety razor having cooperating blade-supporting members permanently connected in superposed relation and arranged to be spaced to receive an apertured blade presented transversely therebetween, and a handle having a key arranged to slide longitudinally therein in registration with the aperture of the blade and being free to turn with the blade only when it has been passed through one of said blade-supporting members.

45. 8. A safety razor having cooperating blade-clamping members organized and adapted to receive a blade presented transversely in crosswise position between them, and means for drawing said members into clamping relation having a blade-engaging portion constructed to engage

and swing the blade about an axis perpendicular thereto into shaving position.

9. A safety razor having cap and guard members organized and adapted to receive a blade presented transversely between them in crosswise 5 position, blade-swinging means constructed and arranged to engage the blade as presented and swing it about an axis at right angles to the plane of its surface, clamping means for the cap and guard members, and a single operating device 10 for actuating first one and then the other of said means.

10. A safety razor having cooperating blade-clamping members constructed and arranged to receive a blade presented crosswise to the razor, 15 and a tubular handle having therein a nut and bolt equipped with a blade-swinging key arranged to slide longitudinally as a unit into and out of clamping engagement with one of said blade-clamping members.

20. 11. A safety razor having cooperating blade-clamping members constructed and arranged to receive a blade presented crosswise to the razor, and a hollow handle having therein a nut and bolt equipped with a blade-swinging key arranged 25 to turn as a unit into and out of interlocking engagement with one of said blade-clamping members.

12. A safety razor having cooperating blade-shaping members loosely connected to admit a 30 blade presented endwise between them from one side of the razor, and clamping means extending from one member to the other arranged to drop down clear of the path of the blade and having a blade-engaging portion adapted to swing the 35 blade into lengthwise position.

13. A safety razor having cooperating blade-engaging members loosely connected to admit the end of an apertured blade presented crosswise from one side of the razor, and a blade-engaging 40 element located initially in one of said members and shaped to pass through the blade aperture, said element having a blade-engaging face and a face adapted to interlock with the other of said members after the element has been lifted 45 through the blade aperture and while acting to swing said blade into lengthwise position in the razor.

14. A safety razor having co-operating cap and guard members, means for holding them separated to receive a blade presented crosswise between them, and means in the razor movable to engage the blade in mid-position as presented and mechanically turn it into shaving position between the cap and guard.

55. 15. A safety razor having co-operating blade clamping members, means for holding them spaced from each other to receive an internally apertured blade presented crosswise to the razor, and a key acting to enter the aperture of the 60 blade and arrest it in mid-position in the razor and thereafter to turn the blade into shaving position between said clamping members.

16. A safety razor having blade clamping members, means for centering therein a blade having 65 a shoulder in its periphery, a blade stop in the razor, and means acting first to swing the blade to engage its shoulder against said stop and then to move the clamping members while the blade is so held.

70. NICHOLAS TESTI.
